UNITED STATES PATENT OFFICE

125,453

DESIGN FOR A GARDEN TOOL OR THE LIKE

Forest J. Morasco, Randolph, N. Y.

Application May 8, 1940, Serial No. 92,223

Term of patent 3½ years

To all whom it may concern:

Be it known that I, Forest J. Morasco, a citizen of the United States, residing at Randolph, in the county of Cattaraugus and State of New York, have invented a new, original, and ornamental Design for a Garden Tool or the like, of which the following is a specification, reference being had to the accompanying drawing, forming part thereof.

I claim:

The ornamental design for a garden tool or the like, as shown.

FOREST J. MORASCO.
